[57] CLAIM

The ornamental design for a mirror unit for trucks or the like, as shown and described.

DESCRIPTION

FIG. 1 is a front elevation view of a mirror unit for trucks showing our new design;

FIG. 2 is a rear elevation view thereof;

FIG. 3 is a top plan view thereof;

FIG. 4 is a bottom plan view thereof;

FIG. 5 is a left side elevation view thereof;

FIG. 6 is a right side elevation view thereof; and

FIG. 7 is an enlarged sectional view thereof taken along line 7—7 of FIG. 1.

Fig. 1.

Fig. 2.
